UNITED STATES PATENT OFFICE.

PERRY R. JORDAN AND WILLIAM WRIGHT, OF ADAMSVILLE, ALABAMA.

COKE-LOADER.

1,072,731.

Specification of Letters Patent.

Patented Sept. 9, 1913.

Application filed August 22, 1912. Serial No. 716,527.

To all whom it may concern:

Be it known that we, PERRY R. JORDAN and WILLIAM WRIGHT, citizens of the United States, residing at Adamsville, in the county 5 of Jefferson and State of Alabama, have invented new and useful Improvements in Coke-Loaders, of which the following is a specification.

Our invention relates to coke loaders.

10 The object of our invention is to provide a more efficient device than that shown in the application of Perry R. Jordan #600,333, filed Dec. 31, 1910 for improvement in coke loaders which efficiency is obtained by the 15 provision of suitable means to scrape and remove ashes or other foreign matters from the track or path traversed by the machine.

Said improvement is hereinafter described and illustrated in the accompanying drawings.

20 In said drawings:—Figure 1 is a side elevation of the machine. Fig. 2 is a plan view showing the gatherers or scoops and other receptacle, the latter being shown broken 25 away and in section, and, Fig. 3 is a detail perspective view of one of the scrapers.

Referring to the drawings, the machine is designated 1 and said machine is composed of parts similar to that shown in the pending application Serial Number 600,333 referred to, except that the screen device and chute for the screenings as shown in said pending application are omitted.

Referring briefly to said machine, the 35 same is shown as a wheel vehicle, the rear wheels 2 of which are driven from a suitable motor 3 mounted upon the frame 4 of the machine. Said motor also drives an endless coke conveyer 5, and a feeder device to 40 supply the coke to the conveyer. Said feeder device comprises a rotary drum having circular heads 6 between which is secured a hollow drum body such as 7, to which drum body coke engaging rakes or 45 the like 8 are fastened. Through the drum heads 6 extends a shaft 9 on which said heads are mounted and on which shaft is also mounted a sprocket wheel 10 adapted to be suitably driven by a connection with 50 the engine to impart motion to the feeder.

Referring now to the improved feature of the device, which consists in means for removing ashes or other foreign matter from the track or path traversed by the machine, 55 the frame 4 has supported thereon as by means of brackets 11, suitable scrapers 12

preferably arranged diagonally below the machine so as to operate upon the path traversed by the machine, to scrape ashes or other dirt from said path and work the 60 same to one side of the vehicle where it may be taken up or removed by scoops, to be hereinafter referred to.

One of the heads 6 is provided with one or more openings 13. On the exterior of the head having the openings 13, are provided a suitable number of scoops such as 14 which scoops are open at a portion thereof and lead to the openings 13. Said scoops are provided with a mouth or the like at 15 to 70 facilitate engagement with the ashes or the like moved to one side of the machine by the scrapers 12.

It will be realized that as the feeder revolves, that the scoops turn therewith and 75 take up or remove the ashes from the path traversed, which ashes fall from the scoops through the openings 13, into the drum 7. As the machine advances the first time, the major portion of the ashes in its path are 80 taken up or collected by the scoops. The ashes remaining in the path however, are deflected or moved to one side by the scrapers 12 so that they can be gathered or collected by the machine upon the next trip, 85 which would be in a path adjacent and parallel to the first path. One or more doors 16 are provided in the drum 7 so that the collected ashes or the like may be removed 90 therefrom.

It will be seen that two of the scrapers 12 are provided one in front of and the other in the rear of the drive wheels 2. One of said scrapers operates when the vehicle travels in one direction and the other 95 operates when the vehicle is traveling in the opposite direction.

It is clear that changes within the details of construction may be made without departing from the spirit and scope of the ap- 100 pended claims.

Having thus described our invention, what we claim is:—

1. In a machine of the class described, a shaft, a receptacle having a side head, said shaft rotatably mounting said receptacle, means to rotate said shaft, a door for said receptacle, said side head provided with an opening communicating with the interior of the receptacle adjacent the shaft, and a 110 scoop fixed to said side head delivering material to said receptacle.

2. In a machine of the class described, a scraper arranged diagonally operating upon the path traversed by the machine, a rotary device having scoop means to engage the scraped material, and a receptacle in said rotary device to which said gathered material is delivered.
3. In a machine of the class described, a scraper operating upon the path traversed by the machine, a rotary device having an end plate provided with a series of scoops thereon to engage the scraped material, said plate provided with an opening through which the material is delivered, a receptacle in said rotary device to which said opening leads, said receptacle provided with an opening through which the material may be removed, and means to cover said opening.
4. In a machine of the class described, a scraper arranged diagonally to engage the path traversed by the machine, a rotary coke feeder device comprising a receptacle, an end plate for said receptacle, said receptacle provided with an opening leading to said receptacle, and scoops fixed on said end plate delivering scooped material to the receptacle, said receptacle provided with an opening through which the scooped material may be removed, and a door covering said latter opening.

PERRY R. JORDAN.
WILLIAM WRIGHT.
